ALARM DEVICE

Joseph Lyska, Detroit, Mich.

Application October 5, 1939, Serial No. 298,048

6 Claims. (Cl. 58—16)

My invention relates to a new and useful improvement in an alarm device adapted for being worn on the arm, wrist or other part of a person's body and intended as a means for awakening the person at a predetermined time.

It is an object of the present invention to provide a device of this class which will be simple in structure, economical of manufacture, durable, compact, light, easily and quickly attached to a person's body and of high efficiency.

Another object of the invention is the provision of the device of this class so arranged and constructed that a tapping member may be caused to oscillate and strike the person's body at a predetermined time in order to awaken the person.

Other objects will appear hereinafter. The invention consists in the construction and arrangement of parts hereinafter described and claimed.

The invention will be best understood by a reference to the accompanying drawings which form a part of this specification and in which:

Fig. 1 is a top plan view of the invention showing it applied to a person's arm.

Fig. 2 is a top plan view of the invention slightly enlarged with parts broken away.

Fig. 3 is a sectional view taken on line 3—3 of Fig. 1, slightly enlarged.

Fig. 4 is a sectional view taken on line 4—4 of Fig. 3.

Fig. 5 is a fragmentary view taken on line 5—5 of Fig. 3.

Fig. 6 is a sectional view taken on line 6—6 of Fig. 5.

Fig. 7 is a detail view of a portion of the device appearing in Fig. 4.

Fig. 8 is a fragmentary sectional view taken on line 8—8 of Fig. 7.

Fig. 9 is a fragmentary side elevational view of a release mechanism used in the invention.

Fig. 10 is a view similar to Fig. 9 showing the release mechanism in another position.

Fig. 11 is a fragmentary sectional view taken on line 11—11 of Fig. 2 and slightly reduced.

As shown in the drawings, the invention comprises a housing 17 having a cover 18, in which is mounted a transparent lens 19, positioned over a dial 20, forming a part of the clock mechanism 21, which in general is of a common construction used for driving the hands 22 and 23.

The shaft 24 serves to drive the minute hand and the sleeve 25 serves to drive the hour hand. Press fitted over this sleeve 25 and rotating in unison therewith is a sleeve 40, carrying at its base the gear 39 provided with the teeth 42. Em-

bracing this sleeve 40 is a hub 26 of the gear 27 having the depending flange 28 on which are formed the teeth 29, meshing with a gear 29' fixedly mounted on the stem 30. An upwardly projecting circular flange 31 carries a pointer or hand 64 cooperating with the dial 20 to determine the relative position of rotation of the gear 27. Embracing this flange 31 is an eyelet 32 formed in the arm 33, intermediate its ends, this arm being fastened at its downwardly offset end 34 to the housing of the clock mechanism 21. The opposite or free end of the arm 35 serves to engage an arm 36 projecting outwardly from the pivotally mounted detent 37. This detent 37 engages the ratchet teeth of an escapement wheel 43 which is fixedly mounted on a rotatable shaft 44 on which is also fixedly mounted a gear 45. This gear 45 meshes with the gear 46 fixedly mounted on the rotatable shaft 47 on which is also fixedly mounted a gear 48. The gear 48 meshes with the gear 49 which is free to rotate on the shaft 50. A ratchet 52 is mounted on the sleeve 51, which embraces the shaft 50. The teeth of the ratchet 52 engage the pawl 53, which is actuated by the spring 54. The shaft 50, the sleeve 51, the ratchet 52, and the gear 57, are relatively fixed to rotate as a unit. A clock spring 56 is secured at its inner end to the shaft 50, and at its outer end to the frame of the clock, and transmits its driving force through the shaft 50, and gears 57, 58 and 59 to drive the elements 61, 62. Winding force is transmitted from the knob 60, through gearing 59, 58, 57 and shaft 50 to the spring 56. During the winding operation the ratchet 52 rides idly under the pawl 53. When the escapement 37, 43 is released, the gear 49 is rotated by the spring 56, through the shaft 50, sleeve 51, ratchet 52, and pawl 53 which is attached to the gear 49. The arm 61 is simultaneously rotated by the spring 56, and the spring tapper 62 is actuated by the rotation of the arm 61.

The spring drive hereinabove described is old in the art and forms no part of the invention in itself, apart from the combination in which it operates. As the arm 61 rides under this tapper it will raise it into the elevated dotted-line position shown in Figure 11. When the arm 61 disengages therewith, this tapper 62 will spring downwardly into the lower dotted-line position shown in Figure 11 so as to strike the arm of the wearer, there being a suitable slot formed in the bottom 66 of the case. The construction is such that when the device is strapped upon the arm 58 of the wearer and the clock mechanism wound

by means of the stem, the hub 26 may be rotated through gear 29 and stem 30 to any desired position, the pointer 64 indicating its position. This hub carries a notch 38 and projecting upwardly from the gear 39 is a spring arm 41. When the notch 38 registers with the spring 41 the gear or hub 26 will move downwardly into the position shown in Fig. 6 and the arm 35 will move down from the dotted line position shown in Fig. 6 to the full line position, thus disengaging the detent 37. If the stop 66A has been pulled outwardly to disengage the escapement wheel 43, this escapement wheel 43 may be permitted to rotate, thus permitting a rotation of the shaft or stem 60 through the gearing described to bring about the tapping of the arm by the taper 62.

In use, after the device is strapped upon the wrist the hub 26 may be rotated to any desired position relatively to the shaft 24 and the sleeve 25 which drive the minute and hour hands. This hub 26 will, of course, be riding on the spring 41 as shown in Fig. 10 and the arm 35 will be flexed upwardly against its resiliency into the dotted line position shown in Fig. 6 so as to engage the arm 36, and lock the detent against rocking movement. As the clock mechanism continues to operate the gear 42 will rotate so as to bring the spring 41 into registration with the notch 38 in which event the parts will move to the full line position shown in Fig. 6 so that the arm 35 will clear the detent arm 36 and permit operation. The spring 56, which of course, will have been previously wound, will effect a rotation of the gear 57 and thus through the gear 58 and the gear 59 bring about a rotation of the shaft 60. As the shaft 60 rotates the spring arm 62 will be alternately raised and released for springing downwardly through the slot formed in the base of the housing so that the taper 62 will be permitted to strike the wrist of the wearer.

In this way, there is provided an alarm mechanism which may be set to any desired time and which, when set off, will serve to awaken a person wearing the device without producing any noise and without producing the shock which sometimes is effected by waking a person with a loud noise.

It is recognized that various changes and modifications may be made in the detail of structure without departing from the general nature of the invention and it is the intention to embrace such modifications within the claims set out herein.

What I claim is:

1. A device of the class described, comprising: a housing adapted for attachment to a wearer, said housing adjacent the wearer having an opening formed therein; a clock mechanism in said housing; a flexible arm fixedly mounted at one end and adapted, upon being released after flexing in one direction, for springing outwardly of said housing through said opening into engagement with the body of a wearer; a rotatable shaft; means on said rotatable shaft for flexing said arm inwardly of said housing and releasing the same for springing outwardly through said opening; spring driven means for rotating said rotatable shaft; a gearing rotatable upon operation of said spring driven means; a releasable member for preventing rotation of said gearing; and means operable by said clock mechanism, for releasing said releasable member.

2. A device of the class described, comprising:

a housing adapted for attachment to the arm of a wearer, said housing at the side adjacent the arm, having a slot formed therein; a spring member connected at one end in said housing and overlying said slot and adapted, upon release after flexing in one direction, for springing outwardly of said slot into engagement with the arm of a wearer; means for alternately flexing and releasing said member; spring driven means for operating said flexing and releasing means; a control mechanism for preventing operation of said spring driven means; and means, operable by said spring driven means, for releasing said control mechanism.

3. A device of the class described, comprising: a housing adapted for attachment to the arm of a wearer and having a slot formed in the side adjacent the arm; a flexible member in said housing attached at one end to said housing and overlying said slot and adapted, upon release subsequent to flexing inwardly of said housing, for springing outwardly through said slot and striking the arm of the wearer; a rotatable shaft; means on said rotatable shaft for alternately flexing and releasing said flexible member; a spring driven mechanism for rotating said shaft; a control for controlling the operation of said spring driven mechanism; and means, operable by said spring driven mechanism, for releasing said control.

4. A device of the class described, comprising: a housing adapted for attachment to the arm of a wearer, said housing having a slot formed in the side adjacent the arm of the wearer; a resilient member secured at one end to said housing and overlying, at its free end, said slot and adapted, upon release subsequent to being flexed inwardly of said housing, for swinging outwardly through said slot into engagement with the arm of the wearer; a rotatable shaft; a laterally projectable engagement member projecting through said shaft and adapted for engaging the free end of said resilient member and flexing the same inwardly of said housing and riding out of engagement therewith upon further rotation of said shaft; a spring driven mechanism for rotating said shaft; a control mechanism for controlling the operation of said spring driven mechanism; means for releasing said control mechanism; and means associated with said spring driven mechanism for determining the release of said control.

5. A device of the class described, comprising: a housing adapted for attachment to the arm of a wearer, said housing having a slot formed in the side adjacent the arm of the wearer; a resilient member secured at one end to said housing and overlying, at its free end, said slot and adapted, upon release subsequent to being flexed inwardly of said housing, for swinging outwardly through said slot into engagement with the arm of the wearer; a rotatable shaft; a laterally projectable engagement member projecting through said shaft and adapted for engaging the free end of said resilient member and flexing the same inwardly of said housing and riding out of engagement therewith upon further rotation of said shaft; a spring driven mechanism for rotating said shaft; a control mechanism for controlling the operation of said spring driven mechanism; means for releasing said control mechanism; and rotatable means for preventing release of said control until the rotation of said rotatable means, to a predetermined position, relatively thereto.

6. A device of the class described, comprising:

a housing adapted for attachment to the arm of a wearer, said housing having a slot formed in the side adjacent the arm of the wearer; a resilient member secured at one end to said housing and overlying, at its free end, said slot and adapted, upon release subsequent to being flexed inwardly of said housing, for swinging outwardly through said slot into engagement with the arm of the wearer; a rotatable shaft; a laterally projectable engagement member projecting through said shaft and adapted for engaging the free end of said resilient member and flexing the same inwardly of said housing and riding out of engage-

ment therewith upon further rotation of said shaft; a spring driven mechanism for rotating said shaft; a control mechanism for controlling the operation of said spring driven mechanism; 5 means for releasing said control mechanism; rotatable means for preventing release of said control until the rotation of said rotatable means to a predetermined position relatively thereto; and means for manually rotating said rotatable 10 means to a predetermined position, said rotatable means being rotatable by said spring driven mechanism.
